UNITED STATES PATENT OFFICE.

ERASTUS E. WINKLEY, OF LYNN, MASSACHUSETTS, ASSIGNOR TO UNITED SHOE MACHINERY CORPORATION, OF PATERSON, NEW JERSEY, A CORPORATION OF NEW JERSEY.

HEEL PRESS.

Application filed December 19, 1916, Serial No. 137,837. Renewed July 10, 1922. Serial No. 573,918.

To all whom it may concern:

Be it known that I, ERASTUS E. WINKLEY, a citizen of the United States, residing at Lynn, in the county of Essex and State of Massachusetts, have invented certain new and useful Improvements in Heel Presses; and I do hereby declare the following to be a full, clear, and exact description of the invention, such as will enable others skilled 10 in the art to which it appertains to make and use the same.

This invention relates to a press into which articles may be introduced successively, and in which they are held under 15 pressure for a substantial length of time, and then discharged successively.

One object of the invention is to produce a press, of the type in question, which may be actuated with the expenditure of a small 20 amount of power, such as may be furnished, for example, by the actuation of a manually operable lever or treadle. Machines of the kind in question have heretofore been proposed in which a series of clamping- 25 devices, adapted for holding heel-piles under pressure, are mounted upon an endless conveyor or chain, and in which the chain is given a step-by-step motion by the actuation of a treadle, while each clamping- 30 device in turn is opened to receive a pile, and closed to clamp the pile, by means of stationary cam-devices operable upon the clamp-mechanism in consequence of its relative movement with the chain.

In accordance with the present invention 35 the amount of power necessary for operating the machine is reduced by the provision of means which act upon the clamping-devices independently of their movements with 40 the chain.

Other objects of the invention are to improve the construction and arrangement of the clamping-devices, and of the means for ejecting the heel-blanks from the press, and 45 to these ends the invention resides in various features of construction which will be pointed out in connection with the following description of the preferred embodiment of the invention.

In the accompanying drawings Figure 1 50 is a side-elevation of a machine embodying the present invention. Fig. 2 is a side-elevation of portions of the mechanism shown in Fig. 1, but on a larger scale. Fig. 3 is

a detailed view, in side-elevation of a part 55 of the actuating-mechanism. Fig. 4 is a vertical section on the line 4—4 in Fig. 2. Fig. 5 is a plan-view of a part of the machine shown in Fig. 2; and Figs. 6 and 7 are, respectively, an end-elevation and a 60 side-elevation of one of the clamps.

The invention is illustrated as embodied in a machine which is designed particularly for receiving heel-piles immediately after they have been assembled, and for holding 65 these piles under pressure for a sufficient length of time to permit the drying of the cement by which the layers of material are held together.

The machine comprises two pairs of 70 sprocket-wheels 10 and 12, about which two endless sprocket-chains 14 are stretched. The wheels are journaled on horizontal shafts 16 and 18 supported upon a framework 20, the wheels of each pair being integral and turning loosely on the corresponding shaft.

The chains 14 support a series of clamps. As shown particularly in Figs. 6 and 7, 75 each clamp comprises a base-plate 22 which is screwed upon specially formed links of the two chains. The heel-pile is clamped between two jaws in the form of plates 24 and 26, with flat opposite faces. The jaw 24 is mounted on the outer end of a plunger 80 85 28 which slides in a guideway 30 projecting inwardly from the base-plate 22. A spring 32, enclosed within the guideway and acting upon a shoulder on the plunger, tends to move the jaw 24 towards the jaw 26, but 90 this movement is limited, when the clamp is empty, by stop-nuts 34 on the free end of the plunger.

The jaw 26 is provided with two trunnions 36 which are received in holes in two arms 38 and 40. The arm 38 is fixed rigidly to the base-plate 22, while the arm 40 is mounted, on a pivot 42, between parallel lugs 43 projecting from the guideway 30. A lug 44, integral with the arm 40, projects between the lugs 43 and is connected to one end of a tension-spring 46, of which the other end is connected to the guideway. This spring tends to swing the arm 40 towards the arm 38, and thus to maintain the engagement between the arms and the trunnions 36. The arms are provided each with a series of holes, however,

and in adjusting the machine for heel-piles of different heights the arm 40 may be swung away from the arm 38, thus releasing the trunnions, which may then be introduced into any pair of the holes so as to adjust the distance between the clamp-jaws.

When a heel-pile is in the clamp it is held compressed by the action of the spring 32. When the heel-pile is to be removed and a fresh pile introduced, the clamp-jaw 24 must be moved away from the jaws 26, against the force of the spring 32, and the mechanism for this purpose is shown particularly in Figs. 2, 4 and 6. An annular plate 48 is fixed to the spokes of each of the sprocket-wheels 12, and each plate 48 carries a series of pivot-studs 50, upon which bell-crank levers 52 are mounted. The shorter arm of each lever is connected to a hook 54, by means of a pivot 56. The hooks cooperate with pins 60 which project in opposite directions from lugs 58 integral with each of the clamp-jaws 24.

The bell-crank levers 52 are actuated by means of two stationary cam-discs 62, of which one is fixed on the shaft 18, while the other is screwed to the frame of the machine. Each bell-crank lever carries a roller 63 which engages the periphery of one of the cam-discs, and as the discs are exactly similar in form and position, the corresponding bell-crank levers on opposite sides of the machine are actuated simultaneously in consequence of the rotation of the sprocket-wheels and the plates 48 about the shaft 18.

Each hook 54 is provided, as shown in dotted lines in Fig. 2, with a lug 65 which is engaged by one end of a spring 64. The spring is coiled around the corresponding pivot 50 and engages, at its other end, a pin 68 projecting from the plate 48. This spring tends to swing the hook upon the pivot 65 in a counter-clockwise direction, as seen in Fig. 2, but this swinging movement is limited by the engagement of a second lug 70, upon the hook, with a stop-pin 72 projecting from the bell-crank lever. The spring 64 also acts to rock the bell-crank lever in a direction to hold the roller 63 in engagement with the cam 62.

Assuming the sprocket-wheels to rotate in a counter-clockwise direction in Fig. 2, each cam-roller 63, when at the bottom of the corresponding cam, engages a high point upon the cam-surface. The corresponding hook is thereby retracted toward the centre of rotation. At the same time the hook is swung rearwardly, upon the pivot 56, by the engagement of a stationary cam-member 76 with a pin 78 projecting laterally from the hook. Accordingly, the hook is held, at this time, within and behind the corresponding pin 60. The roller next encounters an inwardly-inclined portion 74 of the cam-disc 62, whereupon the spring 64 rocks the bell-

crank lever in a direction to throw the hook outwardly. At the same time the pin 78 passes beyond the cam-member 76, so that as soon as the end of the hook has passed beyond the pin 60 the spring 64 acts to swing the hook into position to engage the pin 60. By the continued rotation of the sprocket-wheels the cam-roller is caused to encounter a rise 80 on the cam, which swings the bell-crank lever in a direction to cause the hook to pull the pin 60 inwardly, thus moving the clamp-jaw 24 away from the jaw 26 preparatory to the ejection of the heel-pile from the clamp.

At the point where the chains, in their straight upper stretches, leave the sprocket-wheels, it is necessary to disengage the hooks from the pins 60. Accordingly, the cam-discs 62 are provided with depressions 82, which permit the hooks to be moved outwardly (upwardly), and then, by the continued rotation of the sprocket-wheels, the pins 78 on each hook are brought into engagement with one or the other of two trip-members 84 and 85, located alongside the paths of movement of the hooks. The trip-member 84 is fixed on the upper end of an upright 86 secured to one cam-disc 62, while the trip-member 85 is fixed to a plate 124 constituting a part of the frame of the machine. By engagement of the pins with the trip-members the hooks are momentarily retarded, so that they are swung backwardly out of engagement with the corresponding pins 60, and when the pins 78 have wiped past the trip-members the pins 60 have passed beyond the paths of movement of the hooks.

After the disengagement of the hooks from the pins 60 the cam-rollers engage rises on the cam-discs 62, thus restoring the bell-crank levers to their original positions, and each hook is then carried idly from the upper to the lower part of its path of movement.

The chains 14 are given a step-by-step advancing movement by means of treadle-mechanism. A ring 90 is fixed to one of the sprocket-wheels 10, and this ring carries a series of pins 92. The pins cooperate with a dog 94 connected, by a pivot 96, with a skeleton-lever 98. This lever turns loosely on the shaft 16. The dog is held normally in a downwardly-swung position by means of a spring 100 connecting the dog and the lever 98, but the downward movement of the dog is limited by engagement of a stop-arm 102 thereon with a lug projecting from the lever 98, as shown in dotted lines in Fig. 3.

The lever 98 is connected, by a rod 104, with an arm 106 fixed on a rock-shaft 108. The rock-shaft is journaled upon the frame of the machine, and a treadle-lever 110 is fixed to the rock-shaft. When the treadle

is depressed the lever 98 is swung in a direction to cause the dog 94 to push against one of the pins 92, and thus to rotate the sprocket-wheels 10. This rotation is transmitted to the chains, and through them to the sprocket-wheels 12 and the mechanism by which the clamps are opened.

In order to limit the movement of the chains so caused exactly to the amplitude 10 of the space between two successive clamps, a detent-arm 116 is mounted on a pivot 118 projecting from the framework 20. This detent-arm is provided with a pin 122 which engages a cam-path 120 formed on the inner 15 side of the lever 98. The cam-path is so shaped that during the first part of the movement, just described, of the lever 98, the detent-arm is swung downwardly, so that when the pin 92 which is at the moment 20 engaged by the dog 94 has been brought to the required point it engages and is arrested by the end of the detent-arm, as shown in dotted lines in Fig. 3.

The return-movement is imparted to the 25 lever 98 and the treadle by means of a spring 112 which is attached, at one end, to the upper arm 114 of the lever 98 and, at the other end, to the framework 20. This return-movement is limited by the engagement 30 of the pin 122 with the closed end of the cam-path 120, as shown in dotted lines in Fig. 1.

As each clamp, after receiving a heel-pile and passing through the entire path of motion provided by the chain, returns to its original position, it is necessary to eject the heel-pile from the clamp to provide for the reception of a fresh pile. Since the paste by which the lifts of the heel-pile are secured together may also stick the heel-pile to the clamp-jaw 24, means are provided for pressing the pile laterally with sufficient force to loosen it from the jaw. For this purpose a plate 126 (Fig. 5) is mounted 40 upon the frame-plate 124, the plate 126 having a beveled extremity which overhangs the clamp-jaw 24 as the latter passes by. The beveled end of the plate 126 encounters the heel-pile and forces it laterally from its 45 original position on the clamp-jaw 24. The jaw 24 is provided with a short flange 128 on its rear edge, to prevent the pile from being turned, by its engagement with the plate 126, sufficiently to interfere with the subsequent ejection of the pile from the clamp.

The heel-pile is ejected laterally from the clamp by means of an ejector in the form of a plunger 130, which slides in a guideway 132 on the top of the plate 126. The ejector 50 is actuated by means of an arm 134, which is pivoted on a stud 136 carried by one arm of a bell-crank lever 138. This lever is mounted on a pivot 139 rising from the frame-member 124, and the longer arm of the lever is connected, by a link 140, with

the plunger 130. The arm 134 has a lug 135 at its free end, and this lug lies normally in the path of movement of the pins 60. Accordingly, as each pin comes in engagement with the lug 135 it draws the arm 134 to the left, thus rocking the bell-crank lever 138 and causing the plunger 130 to strike the heel-pile in the clamp which at the time is in proper position, whereby the pile is ejected from the clamp. The arm 134 is 70 provided with a pin 142 which projects downwardly into an inclined guideway 144 on top of the frame-member 124, and this guideway swings the arm 134 away from the pin 60, so as to cause the lug 135 to disengage the pin after sufficient movement has been imparted to the ejector. The parts are then returned to their normal position by a tension-spring 146 which is attached to a lug 80 on the arm 134. 85

The chain comes to rest with the clamp from which the heel-pile has just been ejected, abreast of a gage-plate 152. This plate overhangs the depressed lower jaw of the empty clamp, and its edge serves as a 90 gage against which the operator may press a fresh heel-pile in introducing it to the clamp. The gage-plate is mounted on the frame-member 124 and is adjustable, through a screw-and-slot connection, according to the size of the heel-piles operated upon. 95

Between the sprocket-wheels the upper stretches of the chains are supported by horizontal rails 148 on the frame of the machine. The connection of each clamp with a single link only of each chain does not interfere with the assumption of the necessary curvature in the chains in passing around the sprocket-wheels, as shown in 100 Fig. 2, but to steady the clamps, when they are at the top of the machine, each base-plate 22 is provided with depending projections 150 (Fig. 7) which engage links behind and in front of those to which the base-plate is fixed. 110

The pin-and-hole connections between the clamp-jaws 26 and the arms 38 and 40, beside providing for convenient adjustment as aforesaid, have also the advantage that 115 they permit angular movement of the clamp-jaws by which they may accommodate themselves to the shapes of the heel-piles; and while the machine is illustrated as operating on piles with parallel upper and lower surfaces, it will be apparent that it will operate with equal facility upon piles in which wedge-lifts have been used and which are, accordingly higher at the rear than at the breast. 120

When used as a drying press for heel-piles the present machine is preferably located close alongside the heel-building machine, and the operator of the latter, after the formation of each heel-pile, introduces it into 130

the empty clamp of the present machine and then presses the treadle, whereupon the clamp just filled is closed and moved away, while another clamp is brought up and the 5 heel-pile ejected from it, this latter heel-pile having been held under pressure for the considerable time required to move step-by-step throughout the entire path of movement of the chain.

10 Certain features of the present invention, in their broader aspects, relating to the type of heel-press herein disclosed having, in combination, spring closed heel clamps and a device to open the clamps successively actuated by means other than the moving press structure, are not claimed herein but will be found claimed in applicant's co-pending application, Ser. No. 67,814, filed December 20, 1915, renewed July 10, 1922, Ser. No. 20 573,917.

This invention is not limited to the embodiment thereof hereinbefore described and illustrated in the accompanying drawings, but it may be embodied in various other 25 forms within the scope of the following claims.

What is claimed as new, is:—

1. A press having, in combination, a plurality of clamps comprising each a relatively 30 stationary member and a relatively movable member; means for supporting and moving the clamps, as an endless series, past a work-receiving point, each clamp, when at said point, being positioned with its relatively 35 movable member below said stationary member and in position to have an article laid upon its face; and means for opening and closing each clamp in turn when adjacent said point, by movement of the relatively 40 movable clamp-member from and towards the relatively stationary clamp-member.

2. A press having, in combination, a plurality of clamps comprising each two clamp-members with opposed faces; means for 45 supporting and moving the clamps, as an endless series, past a work-receiving point, said point being located in a position where one clamp-member is above the other clamp-member; and means for opening and closing each clamp adjacent said point, said 50 means acting upon the clamp-member which is beneath, at said point, to move it from and towards the cooperating clamp-member.

3. A press having, in combination, a plurality of clamps arranged in an endless series and each having two clamp-members the area of each of which is at least as great as the area of the article to be pressed of which one has a work-receiving face directed outwardly; means for moving the 55 clamps successively to and from a work-receiving point, at which point the article may be laid upon said outwardly-directed work-receiving face; and means for moving 60 said one of the clamp-members of each

clamp first positively away from the co-operating clamp-member, to receive the work, and then yieldingly towards the co-operating clamp-member, to clamp the work. 70

4. A press having, in combination, a series of clamps flexibly connected to form an endless carrier and each comprising an outwardly-facing inner member and an inwardly-facing outer member; means for 75 supporting said carrier and for actuating it to bring each clamp, in succession, to a work-receiving point; a spring associated with the inner member of each clamp and tending to force it outwardly; and means, operable adjacent said point, for retracting the inner member of each clamp in succession, to permit the discharge and replacement of the work therein. 80

5. A press having, in combination, a 85 clamp comprising two members having opposed working-faces, one of said members being provided with pivots upon which it may swing about an axis lying substantially in its face, and means provided with 90 a series of bearings into which said pivots may be introduced alternatively, at different distances from the other clamp-member; and means for moving the latter clamp-member towards and from the former to 95 clamp and release the work.

6. A press having, in combination, a plurality of clamps arranged in an endless series, each clamp comprising a slidably mounted outwardly-facing inner member 100 constituting a work-receiving seat and an inwardly-facing outer member, the inner member being yieldably held toward the outer member by means of an expansion spring, and means for moving the clamps successively to and from a work-receiving point and for sliding the inner member in 105 a direction to compress the spring and hold each clamp open when at said point.

7. A press having, in combination, an 110 endless conveyor; a series of clamps mounted on the conveyor; a wheel about which the conveyor moves; and a series of clamp-controlling devices movable radially on said wheel and cooperable with the clamps, 115 successively, to control the opening of the clamps as they pass a given point.

8. A press having, in combination, an 120 endless conveyor; a series of clamps mounted on the conveyor; a wheel about which the conveyor moves; a series of clamp-controlling devices mounted on the wheel and cooperable with the clamps successively; and cam-mechanism, for actuating said devices, including a common cam concentric 125 with the wheel.

9. A press having, in combination, a rotary member; a series of travelling clamps supported thereby; clamp-controlling devices movably mounted on the rotary mem- 130

ber and cooperating with the clamps; and mechanism for rotating the rotary member step-by-step for causing the clamps to travel past said devices and for actuating said devices at certain points in the rotation of the rotary member.

10. A press having, in combination, a plurality of clamps arranged in an endless series; means for moving the clamps past a given point; an ejector located at said point; and mechanism for actuating the ejector, controlled by engagement with the clamps.

11. A heel press having, in combination, a plurality of clamps arranged in an endless series; means for moving the clamps past a given point; and a breast gage located at said point and arranged to project into each clamp as it arrives at said point to assist in placing a heel in the clamp.

20. 12. A press having, in combination, a series of clamps; and mechanism, for moving the clamps step-by-step, comprising a series of abutments, a pusher operable upon one side of each of said abutments successively, a detent operable upon the opposite sides of successive abutments, and connected mechanism for successively throwing the detent out of operation, actuating the pusher and throwing the detent again into operative position.

30. 13. A press having, in combination, a plurality of clamps arranged in an endless series; means for moving the clamps successively past a given point; a series of clamp-controlling devices movable with the clamps for engaging and opening them as they reach said point; and separate means for positioning said devices relatively to the clamps while in motion and then actuating them transversely to the direction of motion of the clamps to control the opening of the clamps as they pass said point.

40. 14. A press having, in combination, an endless conveyor; a series of clamps carried thereby; a rotary member for actuating the conveyor; a series of clamp-controlling devices mounted to move with said rotary member and co-operable with the clamps, successively, to control the opening thereof as they pass a given point; and means for actuating said devices relatively to said rotary member to open the clamps.

50. 15. A press having, in combination, a rotary member; a series of clamps supported thereby; clamp-controlling devices independent of the clamp structure and movably mounted on said rotary member; and mechanism for rotating the rotary member and for actuating said devices to engage and release the clamps at certain points in the rotation of said rotary member.

60. 16. A press having, in combination, a rotary member, a series of clamp members supported thereby; clamp controlling devices pivotally mounted on said rotary mem-

ber; and a fixed cam for oscillating said devices successively to control the opening and closing of the clamps as they are advanced by said rotary member.

17. A press having, in combination, a rotary member, a series of clamp members supported thereby; a series of radially arranged levers pivoted on said rotary member for controlling the opening and closing of the clamps; and cam mechanism for 75 swinging said levers on the rotary member while it is in motion.

18. A press having, in combination, a rotary member, a series of clamp members supported thereby; a series of radially arranged 80 levers pivoted on said rotary member for controlling the opening and closing of the clamps; a common cam concentric with said rotary member for engaging all of said levers simultaneously but for actuating them successively to perform their clamp controlling function; and a work ejecting device movable across the path of motion of said rotary member.

19. A press having, in combination, a rotary member; a series of clamp members supported thereby; clamp controlling devices in the form of levers of the first class mounted on said rotary member; means for advancing said rotary member intermittently; a centrally mounted cam continuously engaging the inner ends of said levers for actuating one of them to open a clamp at each advance of the rotary member; and a work ejecting device movable into the clamp 100 after it has been opened.

20. A clamp for presses comprising a plunger slidable in a guideway; a work-receiving press-plate rigidly fixed to one end of said plunger; a co-operating press-plate 105 mounted opposite said work-receiving press-plate to tilt towards and from said work-receiving press-plate for self-accommodation to the angularity of the work; and means tending continually to move said plunger in a direction to close to the clamp.

21. A clamp for presses comprising a base plate; side arms rising therefrom; a press-plate provided with trunnions adapted to be received in holes in said side arms for 115 pivotal movement therein; a plunger received in a hole in said base plate; a work-receiving press-plate carried by said plunger; and means tending continually to move said plunger in a direction to close the 120 clamp.

22. A press having, in combination, a plurality of clamps arranged in an endless series; means for moving the clamps successively past a loading point; clamp controlling devices constructed and operating to open the clamps successively to permit clearing each clamp for reloading; and means acting to impart a preliminary dislodging blow to the work and then a blow of a dif- 130

6
ferent character to eject it from the clamp after the operation of said clamp controlling device thereon.

23. A press having, in combination, a plurality of clamps arranged in an endless series; means for moving the clamps successively past a loading station; expansion springs acting normally to hold the clamps closed; clamp-controlling devices operating 10 to open the clamps successively by a compression of said springs on approaching said loading station and to hold the clamps open until they pass said loading station; and means movable across the line of travel of 15 the clamps for ejecting the work before the loading station is reached.

24. A press having, in combination, a rotary member; a series of clamps supported thereby; each clamp comprising an outer 20 press-plate which travels in a fixed orbit and an inner press-plate which may move transversely to the direction of motion of the clamps; and reciprocatory means movable outward for engagement with said movable press-plates and then inward to retract them from said other press-plates by a movement toward the axis of said rotary member.

25. A press having, in combination, a 30 movable heel-clamp adapted to be moved through a heel ejecting station; and heel ejecting means for releasing any heel that adheres to the clamp by a camming action during the movement of the heel-clamp into the ejection station and then ejecting the heel 35 from the clamp.

26. A press having, in combination, a 40 movable heel-clamp adapted to be moved through a heel ejecting station; and heel ejecting means having a part, to be engaged by the heel as the clamp moves into the

ejecting station, shaped to dislodge by a camming action any heel that adheres to the clamp, and another part acting subsequently to eject the heel from the clamp.

27. A press having, in combination, an 45 endless carrier, a series of co-operating heel-clamps mounted thereon each having means associated therewith for normally maintaining the clamps closed, means for actuating said carrier and clamps through clamp-releasing and loading stations, means for successively opening said clamps at said clamp-releasing station and holding them open 50 until loaded with new heels, and means intermediate said two stations for ejecting the 55 present heels from the open clamps.

28. A press having, in combination, an 60 endless carrier, a series of co-operating heel-clamps mounted thereon each having means associated therewith for normally maintaining the clamps closed, means for actuating said carrier and clamps through clamp-releasing and loading stations, and means 65 movable with the carrier for successively releasing said clamps as they arrive at said clamp-releasing station and for maintaining said clamps released until they have been loaded with new heels.

29. A heel press having, in combination, 70 a movable heel-clamp having a spring associated therewith for normally maintaining it closed adapted to be moved through clamp-releasing and loading stations, and common means for releasing the clamp to permit ejection of the pressed heel, for holding the clamp released until the loading station is reached, and for restoring the clamp to the action of its closing spring after it 75 has been loaded with a new heel.

ERASTUS E. WINKLEY.
